UNITED STATES PATENT OFFICE

FREDERIC W. ERICKSON, OF LARCHMONT, NEW YORK

NIGHT AND DAY STADIUM

Application filed July 31, 1930. Serial No. 472,012.

This invention relates to structures quite commonly known as stadiums which are large enclosed areas used for games such as base ball, and frequently employed for other exhibitions and assemblages.

Base ball is a fast game, and the central object of interest is a ball of such small diameter that it must be handled in a strong light not only to enable the players themselves to see and keep track of it, but also that the spectators may follow the plays from the most distant points in the stadium.

As a whole, my present invention relates to the same type of structure as that illustrated and described in Letters Patent No. 1,711,994, issued to me May 7, 1929, to which reference may be had for detailed descriptions of the objects and advantages attained by a stadium structure that can be used at night and regardless of ordinarily inclement weather. As in the structure of said patent, the roof canopy of my present invention comprises a plurality of flexible sheets or strips of material such as canvas, and my present invention has particular reference to the supporting structure of said strips and the method of handling the same. So far as concerns the rest of the structure, such as the playing field and the seating arrangements, the stadium may well be the same as in said patent, and the lighting arrangements may be the same.

With the main object of the present invention being to improve the arrangement of the roof canopy strips and the handling thereof, the said invention consists in the structure and combinations of parts substantially as hereinafter described and claimed.

Of the accompanying drawings:—

Figure 1 is a somewhat diagrammatic perspective view of so much of the stadium as is included in the present invention.

Figure 2 is an end view, omitting the lower portion of the stadium.

Figure 3 is a view similar to a portion of Figure 2, on a larger scale.

Figure 4 is a side elevation of one of the storage drums.

Figure 5 represents a section on line 5—50 of Figure 4 on a larger scale.

Figure 6 illustrates three of the trucks and the upper portions of the canopy strips supported thereby in their marginally overlapping relationship.

Similar reference characters indicate similar parts or features in all of the views.

So far as the playing field and the seating arrangements are concerned, they may be of any well-known or preferred type. Figure 1 illustrates, at opposite sides of the field 12, lower seats 15 and upper seats 16, with protective roofing 17, and towers or columns 19 along opposite sides of the field. As so far referred to, the structure may be the same as that of the parts or members having the same reference numerals in the patent referred to.

In carrying out my present invention, the tops of the towers are connected by taut cables 20 which support the trucks to enable the latter to be adjusted back and forth from the towers to positions over the longitudinal center of the playing field, as hereinafter described.

Each truck comprises side frame members 21 having upper shafts 22 for wheels 23 running on the cables 20 (Figs. 2, 3 and 6), and a lower shaft 24 having sheaves 25. A cross bar 26 connecting the frame members 21 is coupled at 27 to a cable 28 extending in opposite directions therefrom and running over pulleys 29 at the tops of two opposite towers, and down to any suitable winding drums not necessary to illustrate. As indicated by comparing Figures 2 and 6, there are two cables 28 for each pair of trucks that are mounted to meet each other on the cables 20, one of said two cables being for one truck and the other cable for the other truck of the pair. This is to enable the trucks to be shifted in opposite directions.

Mounted on the sheaves 25 of each truck are endless cables 30 the lower ends of which are mounted on sheaves 31 supported by brackets 32 projecting from lower portions of the towers 19. Said cables may be actuated manually or by suitably applied power, as preferred.

A strip 33, of suitable substantially rigid material, connects the two cables 30 of each

truck (Figs. 2 and 6), and to each such strip or bar there is connected the upper transverse edge of a flexible strip 34 of such material as canvas, the upper end portion of each of such strips of canvas having sections of waterproof material indicated at 35 in Figure 1.

The lower edge of each strip 34 is connected to a winding storage drum illustrated as a whole at 36 in Figure 1. The drums 36 are of skeleton structure as presently described, to reduce liability of the canvas, when wound thereon, becoming unduly wet during inclement weather. And of course when the strips include the upper sections 35 of waterproof material, said sections become protective wrappings of the coils of canvas wound on the drums.

As illustrated by Figures 2, 4 and 5, each storage drum comprises a tubular shaft 37 mounted in bearings in brackets 38 supported by the towers 19. Mounted on the shaft 37 are two spiders 39 the multiple arms of which have recessed tips in which cables 40 lie, the ends of said cables being secured to hubs 41 adjustably secured to the shaft so that said cables can be maintained taut and thereby provide a skeleton core upon which the canvas can be wound for storage when the stadium is having its canopy removed from overhead location. In Figure 4 and shaft 37 is illustrated as having a pinion 42 which may be engaged by a suitable driving pinion not necessary to illustrate.

An important feature of the present invention is the making of the canopy strips 34 of such width, and so connecting them with the canopy-adjusting trucks, that they alternate in side-by-side closely overlapping relationship, as indicated in Figure 1 and more clearly illustrated by Figure 6. In other words, both side edges of every strip excepting the two end ones extend either over or under the edges of both of the next strips at opposite sides thereof, thereby ensuring to the utmost a canopy for the playing field which canopy can be adjusted to position to effectually prevent the admission of any appreciable amount of rain down to the playing field.

For use during inclement weather, the strips are drawn up to the positions indicated in Figure 2, the upper end edges being then so close together that little or no rain can enter between them. But when the canopy is not needed, the strips can be drawn down and wound on the drums 36. If it is desired to have some of the canopy open and other portions closed, the strips can be individually operated to effect whatever exposure may be desired.

If some happening such as the approach of a violent storm renders it desirable to remove the entire canopy from overhead position, the trucks can be quickly shifted to

positions close to the towers, and the canvas strips wound up on the storage drums, resulting in the cables 20 being the only permanent rigging left over the playing field. And this may, and preferably usually will be, the condition of the parts during daylight in good weather. For use of the stadium at night, interior lighting arrangements are made such as explained in the patent hereinbefore referred to.

Having now described my invention, I claim:

1. A structure for use with a field for games and other events, said structure having cables crossing the field, movable members mounted on said cables, said member being movable to and from abutting relationship, and flexible canopy sections the upper ends of which are connected to said movable members.

2. A structure for use with a field for games and other events, said structure having tall towers at opposite sides of the field, cables crossing the field and supported by said towers, movable members mounted on said cables, said member being movable to and from abutting relationship, and flexible strips connected to said movable members.

3. A structure for use with a field for games, and other events, said structure having cables crossing the field, movable members mounted on said cables, said member being movable to and from abutting relationship, flexible canopy sections the upper ends of which are connected to said movable members, and means connected with the other ends of said sections for winding them up.

4. A structure for use with a field for games and other events, said structure having cables crossing the field, movable members mounted on said cables, said member being movable to and from abutting relationship, flexible canopy sections the upper ends of which are connected to said movable members, means connected with the other ends of said sections for winding them up, and means for shifting said movable members to different positions along their supporting cables.

5. A structure for use with a field for games and other events, said structure having cables crossing the field, movable members mounted on said cables, said member being movable to and from abutting relationship, and flexible canopy sections overlapping each other along their side edges and operatively connected with said movable members.

6. A roof canopy comprising a plurality of flexible strips, and means for supporting them in alternating side-by-side relationship with both side edges of every strip excepting the end ones extending either under or over the edges of both strips at opposite sides thereof.

7. A roof canopy comprising a plural-

ty of flexible strips, means for supporting them in alternating side-by-side relationship overlapping at both edges with both side edges of every strip excepting the end ones 5 extending either under or over the edges of both strips at opposite sides thereof and means for independently shifting said strips in the direction of their lengths.

8. A roof canopy structure including a 10 plurality of flexible strips having waterproof sections at one end, and winding drums to which the other ends of the strips are connected.

9. A roof canopy structure including a 15 plurality of flexible strips, adjustable supports for the upper ends of the strips, said supports being movable to and from abutting relationship, and winding drums to which the other ends of the strips are connected. 20

10. A structure for use with a field for games and other events, said structure having overhead horizontally movable members, oppositely inclined cables connected to said 25 overhead members, flexible strips connected at their upper ends to said cables, and winding drums to which the lower ends of said strips are connected.

In testimony whereof I have affixed my signature. 30

FREDERIC W. ERICKSON.
